UNITED STATES PATENT OFFICE.

LEO AMARO CARRERAS, OF NEW YORK, N. Y.

HAT-PIN-POINT PROTECTOR.

1,148,211.

Specification of Letters Patent.

Patented July 27, 1915.

Application filed October 31, 1913. Serial No. 798,460.

To all whom it may concern:

Be it known that I, LEO A. CARRERAS, a citizen of the United States, residing at New York, in the county of New York and State 5 of New York, have invented certain new and useful Improvements in Hat-Pin-Point Protectors, of which the following is a specification.

This invention relates to improvements in 10 hat pin point protectors and has for its object to provide a receptacle for a pin point and means for securing said point on said receptacle after it has been projected thereinto.

15 With the above and other objects in view which will be more clearly set forth in the following specification, I have invented the device illustrated in the accompanying drawings in which—

20 Figure 1 is a view of a hat pin showing my device fixed thereon, Fig. 2 is an enlarged sectional view taken on line A—A of Fig. 1, Fig. 3 is a section on line B—B of Fig. 1, and Fig. 4 is a view similar to Fig. 2 shown partly broken away and with the pin clamp raised out of engagement with the pin.

Like reference characters indicate like parts throughout the specification and in the several views in the drawings in which—

30 1 indicates a hat pin having a head 2 and a point 3, and 4 indicates a receptacle having a flaring entrance, a reduced neck 6 and an enlarged portion 7 having a reduced outlet 8 alining with neck 6 and a chamber 9 adapted to inclose the pin point 3.

The portion 7 is provided with an opening 10 with a hinged closure 11 therefor provided with a handle 12 on its outer surface and a clamp 13 projecting from its inner 40 surface which is adapted to engage the pin 1 after it has been projected through the portion 7 and hold it against removal therefrom.

The clamp 13 consists of a pair of opposing leaf springs 14 and 15 having flared ends 16 and 17 and opposing bent out portions 18 and 19 between which the pin is adapted to be held.

The openings through 8 and 9 are adapted 50 to aline the pin directly under the clamp 13, so that when the lid or closure 11 is closed down the pin 1 will enter between the portions 16 and 17 and wedge them apart so as to enter the recess 20 whereby it will be held.

55 The clamping of the pin 1 by the clamp 13

will act to hold said lid closed until it is forcibly opened by means of the knob 12.

Having now described my device that which I claim to be new and desire to procure by Letters Patent is:—

60

1. The described device consisting of a housing for a pin point and a hingedly mounted spring clamp adapted to hold said pin, said clamp extending into the body of said housing, said clamp being hinged to 65 said housing.

2. The described device consisting of a housing for a pin point, a spring clamp adapted to hold said pin, said clamp extending into the body of said housing, said clamp being hinged to said housing, and a hinged closure for said housing to which 70 said clamp is fixed.

3. The described device consisting of a housing for a pin point, a spring clamp 75 adapted to hold said pin, said clamp extending into the body of said housing, said clamp being hinged to said housing, and a hinged closure for said housing to which said clamp is fixed, said clamp when engaging said pin adapted to hold said closure 80 in a closed position.

4. The described device consisting of a receptacle through which a pin is adapted to project, a swinging clamp adapted to engage said pin, said receptacle having an opening directly over said pin, a closure for said opening, said clamp being on said closure, means whereby said pin may be alined under said opening, said means consisting of a pair of opposing necks, and a flaring mouth adjacent one of said necks, said clamp formed of a pair of leaf springs adapted to straddle said pin.

85

5. The described device consisting of a 95 receptacle through which a pin is adapted to project, a swinging clamp adapted to engage said pin, said receptacle having an opening directly over said pin, a closure for said opening, said clamp being on said closure, means whereby said pin may be alined under said opening, said means consisting of a pair of opposing necks, and a flaring mouth adjacent one of said necks, said clamp formed of a pair of leaf springs adapted to 100 straddle said pin, the ends of said springs being flaring in opposing directions.

105

6. The described device consisting of a housing for a pin point, a spring clamp adapted to hold said pin, said clamp extend- 110

ing into the body of said housing, said clamp being hinged to said housing, and a hinged closure for said housing to which said clamp is fixed, said clamp when engaging said pin adapted to hold said closure in a closed position, said springs having flared ends whereby they may be forced apart by said pin.

7. The described device consisting of a 10 housing for a pin point, a spring clamp adapted to hold said pin, said clamp extending into the body of said housing, said clamp being hinged to said housing, a hinged closure for said housing to which

said clamp is fixed, said clamp when engaging said pin adapted to hold said closure in a closed position, said springs having flared ends whereby they may be forced apart by said pin, and opposing grooves transverse of said clamp forming a recess 20 for said pin.

In testimony whereof I affix my signature in presence of two witnesses.

LEO AMARO CARRERAS.
